CLAIM

The ornamental design for a fluid dispensing nozzle, as shown and described.

DESCRIPTION

FIG. 1 is a front left side perspective view of the fluid dispensing nozzle shown in a position of use with a spray can fluid container drawn in broken lines;

FIG. 2 is a bottom left side perspective view of the fluid dispensing nozzle.

FIG. 3 is a top view of the fluid dispensing nozzle.

FIG. 4 is a bottom view of the fluid dispensing nozzle.

FIG. 5 is a left side view of the fluid dispensing nozzle.

FIG. 6 is a right side view of the fluid dispensing nozzle.

FIG. 7 is a back view of the fluid dispensing nozzle; and,

FIG. 8 is a front view of the fluid dispensing nozzle.

The spray can fluid container drawn in broken lines is included for the purpose of showing the environment of use and forms no part of the claimed design.
